CROWN BLOCK CONSTRUCTION

Vladimir B. Sounitsa, Houston, Tex., assignor to
 Emco Derrick & Equipment Company, Los
 Angeles, Calif., a corporation of California

Application December 18, 1937, Serial No. 180,558

4 Claims. (Cl. 308—72)

My invention relates to crown blocks, such as are commonly installed at the upper ends of derricks on oil wells; and my invention particularly relates to a unique bearing assembly which 5 may constitute a part of such a crown block construction.

The crown block commonly employed at the upper end of oil well derricks consists of a plurality of beams which support bearing assemblies in which shafts are rotatable. Mounted on the shafts are sheaves over which the cable, which extends downwardly to the travelling block, is wound. It is an object of my invention to provide 10 a crown block which incorporates in the bearing assembly self-aligning bearings so that bearing alignment may be obtained with no difficulty upon original installation, and so that any changes in position which may occur during the use of the crown block may be automatically compensated 15 for so that bearing alignment will be maintained throughout the period of use of the crown block.

It is a further object of my invention to provide 20 a unique bearing assembly for a crown which is of simple construction consisting essentially of a cast box and a bushing resting on suitable supporting surfaces in the box and without means of attachment thereto, and in which there is provided means engageable by the bushing upon upward movement thereof in order that if, upon 25 raising the crown block shaft from the box, the bushing adheres thereto, it will be disengaged from the shaft and retained in the box, with the result that there will be no danger of the bushing being inadvertently removed from the box and 30 possibly falling downward through the derrick and injuring a workman.

It is a further object of my invention to provide 35 a unique bearing assembly for use as a part of the crown block construction in which the parts are designed so that there is but a minimum of machining. In this way the bearing assembly may be provided at a minimum of cost and yet satisfactorily perform all of the duties necessary 40 for a satisfactory operation. In the preferred form of my invention I provide a box, the lower surface of which is machined so that it may rest on a supporting wall, and within the box I provide a journal which includes journal elements 45 having machined surfaces. Cooperating with the box is a bushing having a bearing consisting of elements having machined surfaces for cooperation with the machined surfaces of the journal elements and also having a shaft supporting wall 50 which is machined and which supports the crown 55

block shaft. If desired, in order to enclose the upper part of the box, a cover may be provided, and this is done in the preferred form of my invention.

It is a further object of my invention to provide 5 a bearing assembly having a unique oiling means for delivering oil to the shaft supporting portion of the bushing.

It is a still further object of my invention to 10 provide a crown block construction in which the assembly of the bearing unit, shaft, and sheaves may be readily secured in position on the supporting means and may be readily released and adjusted into any desired position along the beam. 15

It is also an object of my invention to provide 20 a combination of this character in which when the assembly is released it can be slid along the supporting beams but cannot be raised from position thereon.

It is a further object of my invention to provide 25 a bearing assembly having a simple yet effective means for clamping the box of the assembly in any position along the supporting beam.

Other objects and advantages of my invention 30 will be pointed out in the course of the following detailed description of a preferred form of my invention.

Referring to the drawings:

Fig. 1 is a plan view of a portion of a crown block incorporating the features of my invention.

Fig. 2 is a section through one of the bearing and sheave assemblies and is taken on the line 2—2 of Fig. 1.

Fig. 3 is a cross-section through a bearing assembly of my invention and is taken as indicated by the line 3—3 of Fig. 1.

Fig. 4 is a sectional view taken as indicated by the line 4—4 of Fig. 3.

Fig. 5 is a section through the securing means 40 of my invention and is taken as indicated by the line 5—5 of Fig. 3.

Fig. 6 is a plan view of the box which incorporates a part of my invention.

Fig. 7 is a perspective view showing the bushing 45 which constitutes one of the elements of my invention.

Referring to the drawings in detail, and particularly Figs. 1 and 2, the numeral 11 represents 50 I-beams which constitute supporting beams of my invention and are adapted to be supported at the upper end of the derrick. It will be noted that a plurality of beams 11 extending parallel to each other is provided, and that supported on 55

the beams 11 are sheave assemblies 12, each of which is independently adjustable so that sheaves 14 thereof may be suitably positioned at the upper end of the derrick. As shown best in Figs. 1 and 2, each of the sheave assemblies 12 consists of a pair of bearing assemblies or bearing units 15, each of which is supported on a beam 11, a shaft 16, and the sheave 14 which is mounted on the shaft. As illustrated in the various views, the bearing assembly includes a box 18 which has a lower machined surface 19 adapted to rest on an upper supporting wall 20 of the supporting beam 11. This box 18 of each bearing assembly is shaped to provide a lubricant chamber 21 which may be provided with lubricant, as indicated at 22. Within the chamber 21 there is a journal which is preferably provided in the form of a pair of spaced journal elements 23 which project upwardly from a bottom wall 24 of the box 18. These journal elements provide spherical journal walls 26 which cooperate to provide a spherical journal, and these walls 26 are generated around the same center.

Adapted to cooperate with the box 18 is a bushing 30 which includes a semi-cylindrical shaft supporting wall 31 having an inner machined surface 32 adapted to receive the end of the shaft 16. At the outer ends of the bushings 30 are end walls, such as illustrated at 33 in Fig. 4, having machined surfaces 34 which engage end walls 35 of the shaft 16 to prevent axial movement thereof.

Each bushing 30 is provided with a spherical bearing adapted to seat in the spherical journal 38 and is provided in the form of a pair of longitudinally spaced bearing elements 37 which project downwardly from the wall 31, and which have machined spherical walls 38 which are generated around a point and on a radius the same as that around which the journal walls 26 are generated. As shown in Figs. 3 and 4, the walls 26 and 38 coengage each other, and this constitutes the wall supporting means for the bushing 30 in the box 18. This arrangement permits a universal movement of the bushing 30 and enables alignment of the bearings with the shafts supported thereby.

It will be noted that the bushing 30 merely rests in the box 18 and there is no securing means for securing the same in place. In view of the fact that the end of the shaft is supported by the bushing 30 and the wall 32 is supplied with lubricant, there may be sufficient cohesion between the parts so that when the shaft is raised upward relative to the box the bushing will be raised therewith, and when moved free of the box the cohesion may decrease in strength or the shaft and sheave assemblies may be tilted into such position that the bushing will be released therefrom and fall. Since the assembly is used at the top of the derrick, it may fall to the floor of the derrick and not only cause breakage of the part but may cause serious injury to any workman on the derrick floor.

One of the important features of my invention is a very simple yet effective means of preventing removal of the bushing from the box upon raising the shaft upwardly therefrom. This important object of my invention is quite simply accomplished by providing the upwardly extending wall 40 with an inwardly projecting engageable means in the form of a lug 41. This lug 41 extends inwardly so as to be engageable by the bushing 30 if the bushing 30 is moved upwardly relative to the box 18. In the form of my invention disclosed

herein I prefer to position the lug 41 directly above the end wall 33 but spaced therefrom so that normally there is no engagement between the lug 41 and any part of the bushing 30. This is desirable in order to prevent free movement of the bushing in the box in order to permit alignment of the parts. It will be seen, however, that upon upward movement of the bushing the wall 33 engages the lug 41 and thus prevents further upward movement thereof and separates the same from the end of the shaft 16. This construction, however, after the shaft 16 has been removed does not prevent removal of the bushing 30 by the workman, which may be done by moving the bushing rightwardly (with reference to Fig. 4) so that the lug 41 will not be engaged.

It will be noted that between the bearing elements 37 there is provided a central channel 45 which extends through the body of lubricant 22. For the purpose of lubricating the end of the shaft 16 and the supporting wall 31 there is provided an oil distributing means in the form of an endless belt 46 which extends around the upper part of the shaft and downwardly on opposite sides of the wall 31 and through the channel 45. When the shaft 16 is rotated the endless belt 46 is moved and this carries oil upwardly onto the shaft and between the coengaging surfaces of the shaft and wall 31.

In order to close the upper part of the box 18 I provide a suitable cover 49 which is pivoted to the box, as indicated at 50, and is releasably held in closed position by a suitable latch means 51. Upon releasing the latch means 51 the cover may be swung into an open position which gives free access to the interior of the box 18.

For the purpose of adjustably securing the boxes 18 to the supporting beams 11 I provide a construction which will now be described. Extending outwardly from opposite sides of the box 18 are box flanges 55 which, as shown in Fig. 5, rest directly above the edge portions of beam flanges 56. Each pair of box and beam flanges 56, there being two on each side, constitute a wedge shaped projection due to the fact that either or both of the outer faces 57 and 58 are inclined and thus provide a projection which converges outwardly and is therefore of wedge shape. Adapted to cooperate with each projection is a U-shaped clamp member or block 60 having an outer wall 61 and inwardly projecting walls 62 having inner surfaces 63 adapted to engage the outer faces 57 and 58 of the projection cooperating therewith. As shown in Fig. 5, the clamps are positioned at each side of the beam with the surfaces 63 in coengagement with the surfaces 57 and 58, and it will further be seen that upon forcing the clamps 60 inwardly the boxes are securely pressed and clamped downward against the supporting surface 20 of the supporting beam 11 and thus rigidly secured in any given position along the beam. For the purpose of effecting this clamping action, I provide a bolt means in the form of a carriage bolt 65 which extends laterally through transverse channels 66 which are formed in the bottom wall 24 of the box 18 and extend through the box flanges 55, as shown best in Fig. 5. The walls 61 of the clamps 60 have openings 67 through which the bolt means extends, there being a head 68 on one end of the carriage bolt 65 and a nut 69 on the other end thereof which may be tightened in order to force the clamps 60 together.

It is a feature of the invention that this clamp construction be of simple yet effective design and

that upon loosening the carriage bolt the clamps release their clamping force and permit the box to be adjusted longitudinally of the supporting beam 11. When the clamp means is released the 5 walls 62 still extend inwardly in a surrounding position around the adjacent flanges 55 and 56, and the boxes cannot be raised or removed from the supporting beam 11 by an upward or side- 10 ward movement. This provides a measure of protection and prevents the parts from being accidentally dropped from the top of the derrick.

In the foregoing description I have considered a preferred form of my invention. It should be understood, however, that the principle of my 15 invention may be employed in other forms, and that I do not wish to be limited to the details of construction illustrated herein but wish my invention to be broadly construed in accordance with the appended claims.

20 I claim as my invention:

1. In a crown block assembly of the character described, the combination of: a sheave member having axial shaft elements projecting therefrom; and bearing means to receive said shaft 25 elements, said bearing means each comprising a box having an upwardly faced chamber with a side opening to receive one of said shaft elements, there being in said chamber a support to adjustably receive a bearing bushing, and a bearing 30 bushing in said chamber of said box, said bearing bushing having means on the lower part thereof for cooperative engagement with said support and an essentially semicylindrical wall forming an upwardly faced pocket to receive the shaft 35 element, there being an end wall at the end of said essentially semicylindrical wall to engage the end of the shaft element so as to limit end movement thereof.

2. In a bearing assembly adapted for use as a 40 part of a crown block, the combination of: a box having a spherical journal consisting of two spaced journal elements; a bushing including an essentially semicylindrical shaft supporting wall for supporting a shaft of the crown block, and

having a spherical bearing adapted to seat on said spherical journal, which includes a pair of bearing elements each being adapted to engage and cooperate with one of said journal elements; a detachable cover element passing over said 5 shaft and limiting its upward movement relative to said box; and engageable means positioned on said box so as to be engaged by said bushing should the same be raised upward relative to said box with said shaft after removal of said 10 cover element.

3. In a bearing assembly for use as part of a crown block, the combination of: a box having an upwardly faced pocket defined by a bottom wall and a side wall; a bearing bushing seated 15 in said pocket, said bushing being characterized by having a substantially cylindrical shaft supporting wall; and a lug projecting from said side wall of said box in a position above a part of said bushing, to be engaged by said bushing when 20 the same is raised from its seated position in said pocket and to prevent said bushing from being raised from said pocket as said shaft is raised from its position of operation relative to said box.

4. In a crown block bearing assembly, the combination of: a box having an upwardly faced pocket defined by bottom and side walls; a bearing bushing adjustably seated in said pocket, said bushing being characterized by having a substantially semi-circumferential shaft supporting 25 wall; and means to restrain said bushing from being raised out of said pocket when said shaft is moved upward from its normal position of operation relative to said box, said means comprising a part carried by said box and a part 30 carried by said bushing positioned so as to be normally non-operative but being arranged in such overlapping relation that upon upward movement of said bushing said parts will come into engagement so as to prevent upward movement of said shaft from lifting said bushing out of said pocket. 35 40

WLADIMIR B. SOUNITZA.
